CLAIM

The ornamental design for a controller for tattooing apparatus, as shown and described.

DESCRIPTION

FIG. 1 is a front top perspective view of the controller for tattooing apparatus;

FIG. 2 is a front elevational view of the controller for tattooing apparatus of FIG. 1;

FIG. 3 is a rear elevational view of the controller for tattooing apparatus of FIG. 1;

FIG. 4 is a left side elevational view of the controller for tattooing apparatus of FIG. 1;

FIG. 5 is a right side elevational view of the controller for tattooing apparatus of FIG. 1;

FIG. 6 is a top plan view of the controller for tattooing apparatus of FIG. 1;

FIG. 7 is a bottom plan view of the controller for tattooing apparatus of FIG. 1;

FIG. 8 is a rear top perspective view of the controller for tattooing apparatus; and,

FIG. 9 is a front bottom perspective view of the controller for tattooing apparatus.
